BUS BAR SUPPORT

Lawrence L. Fountain, Wilkinsburg, Pa., assignor
to Westinghouse Electric Corporation, East
Pittsburgh, Pa., a corporation of Pennsylvania

Application November 10, 1944, Serial No. 562,785

5 Claims. (Cl. 174—99)

1

My invention relates, generally, to electrical distribution systems and, more particularly, to multi-phase bus-duct structures of the low impedance type, commonly known as feeder bus-duct.

The close spacing between the conducting bars of a bus-duct structure is conducive to very high stresses on the supporting members when currents of high magnitude flow, as is the case during short-circuit conditions. When rectangular supports and blocks are utilized to encase bus bars of the type disclosed in the copending application of C. F. Wagner and L. L. Fountain, Serial No. 543,936, filed July 7, 1944, the forces between bars impart stresses to the material, comprising a rectangular yoke, which are a combination of shear and tension. When the bus-duct is installed in systems where excessive amounts of current may flow under short-circuit conditions, these forces twist and bend the sides of the rectangular yoke in a manner that leaves the intermediate blocks of insulating material out of compression and they no longer form an adequate supporting structure for the bus-bar angles.

One object of my invention is to provide a bus-duct structure which is an improvement over the structure disclosed in the aforesaid copending application.

Another object of my invention is to provide a bus-duct structure which shall be simple and efficient in operation and which may be economically manufactured and installed.

A more specific object of my invention is to provide a bus-duct structure capable of withstanding the stresses imposed thereon when conducting currents of a high magnitude.

Another object of my invention is to provide for mounting an enclosed bus-duct in a building or other structure.

Other objects of my invention will be explained fully hereinafter or will be apparent to those skilled in the art.

In accordance with one embodiment of my invention, the outer surfaces of the insulating blocks which support the bus-bars in an enclosed bus-duct are curved and the blocks are bound together with a steel yoke which is made from portions of two circles of different diameters, thereby making it impossible for the bus structure and the supporting insulating blocks to turn out of position.

For a fuller understanding of the nature and objects of my invention, reference may be had to the following detailed description, taken in con-

2

junction with the accompanying drawings, in which:

Fig. 1 is a view, in end elevation, of a bus structure embodying the principal features of my invention;

Fig. 2 is a view, in perspective, of the bus structure shown in Fig. 1;

Fig. 3 is a view, in elevation, of a portion of a bus support illustrating a slightly modified form of the structure shown in Figs. 1 and 2.

Fig. 4 is a view, in section, of a modification of the invention, and

Fig. 5 is a view, in section, of another modification of the invention.

Referring to the drawings and particularly to Figs. 1 and 2, the structure shown therein comprises a rectangular housing 10 having right angle bus-bars 11 and 12 and a flat bus-bar 13 disposed within the housing to form a T. As shown, one leg of the right angle bar 11 is paired with one leg of the right angle bar 12. The other leg of the bar 11 is paired with one half of the flat bar 13 and the other leg of the bar 12 is paired with the other half of the bar 13.

Therefore, as explained in the aforesaid copending application, when the bar 11 is connected to phase A of a three-phase system, the bar 13 is connected to phase B and the bar 12 is connected to phase C a mutual coupling is obtained which

provides the desired equivalent of a single phase effect without resorting to a larger number of bus-bars. The bars are preferably insulated from each other throughout their entire length by sheets of insulation 14. Additional strips of insulation 16 and 17 are also provided between the bars where they are supported in the housing 10.

As shown, the bars are supported at desired intervals throughout the length of the housing by a pair of insulating blocks 18, one of which engages the right angle bar 11 and the other of which engages the right angle bar 12, and a third block 19 which engages the flat bar 13. As shown more clearly in Fig. 1, the block 19 is provided with a recess 21 for the bar 13.

The blocks 18 and 19 are provided with curved outer surfaces and are bound together with a metal yoke 22 which, in this particular embodiment, comprises an upper portion 23 and a lower portion 24. The upper portion 23 may be a semi-circular section from a short length of metal pipe of predetermined diameter, for example 9 inches, and the lower portion 24 may be a segmental section from a length of pipe of a slightly larger diameter, for example 10 inches. The sections 23 and 24 may be secured together by bolts 25 ex-

tending through lugs 26 and 27 which may be welded to the sections 23 and 24, respectively.

The blocks 18 and 19 may be retained in position by metal clips 28 of a U-shape which may be spot welded to the yoke 22. Felt strips 29, or other suitable material, may be disposed between the blocks and the yoke 22 to provide a certain amount of resiliency in the support for the bus bars.

As shown, each yoke 22 may be supported in the housing 10 by means of angular brackets 31 which may be welded to the side walls of the housing 10. If desired, the heads of the bolts 25 may be welded to the brackets 31 to retain the bolts in the brackets, thereby facilitating the assembly of the yokes and the bus-bars in the housing. In accordance with the usual practice, the bus-bar structure is manufactured in sections of a suitable length and as many sections as are required are joined together in end-to-end relation when the structure is installed.

The making of the yoke 22 in two sections, an upper and a lower part, each section being a portion of a circle of a different diameter from the other makes it impossible for the bus structure and the supporting insulating blocks to turn out of position because of the relationship of the upper and lower parts with respect to one another. Furthermore, by providing curved outer surfaces on the insulating blocks and securing them together with the curved yoke members, the stresses imposed upon the yoke members become almost entirely of a tensile nature. Consequently, any twisting of the bus-bars will not tend to bend the yoke out of shape and thereby leave the insulating blocks out of compression.

By this method of supporting and bracing the bus-bars with a curved yoke, the unequal forces transmitted by the angular bus-bars during short-circuit conditions are redirected so as to ultimately become tensile stresses instead of deforming shear stresses. In this manner, the structure is enabled to withstand the high stresses produced by the flow of currents of a high magnitude.

The ability of the structure to withstand the forces produced by large amounts of current under short-circuit conditions may be still further increased by providing helical springs 32 between the lugs 26 and the nuts of the bolts 25 as shown in Fig. 3. The springs 32 will be compressed by the forces encountered under short-circuit conditions, thereby increasing the resiliency of the structure and enabling it to withstand the stresses imposed thereon without deforming the yokes 22. In this manner, the two parts of the yokes are returned to their normal positions after the short-circuit conditions are removed and the insulating blocks are retained under compression at all times.

In the modification of the invention shown in Fig. 4, the yoke 22 is formed from channel members 33 and 34 which are bent to conform to the curved surfaces of the blocks 18 and 19. As shown, the blocks 18 and 19 are retained in position by the sides of the channels 33 and 34, respectively.

The two channel sections may be secured together by bolts 35 which extend through lugs 36 and 37 formed on the channels 33 and 34, respectively, by bending the ends of the channels outwardly. Gusset plates 38 and 39 may be welded onto the sides of the channels 33 and 34, respectively, to prevent the lugs 36 and 37 from bending under the stresses imposed upon the channels.

A rib 41 may be formed integrally with the flat bus-bar 13 to prevent its buckling between adjacent supports under short circuit conditions.

As shown in Fig. 4, the bus-duct may be supported in a building or other structure by extending the bolts 35 through the upper side of the housing 10, and connecting hanger bolts 42 to the ends of the bolts 35 by couplings 43. The long bolts 35 may be provided at desired intervals along the duct and the short bolts 25 utilized for the other supports, as shown in Figs. 1 and 2.

When it is desired to mount the bus-duct in the position shown in Fig. 5, hanger brackets 44 may be attached to bolts 45 which extend through opposite sides of the housing 10. As shown, the bolts 45 are also utilized to clamp the two sections of the yoke 22 together at the top of the duct. The short bolts 25 may be utilized as clamping bolts at the bottom of the duct.

From the foregoing description, it is apparent that I have provided for supporting a multi-phase bus-bar structure in a manner which enables it to withstand the forces encountered during the flowing of currents of a high magnitude. The structure may be easily manufactured and readily assembled in an enclosed housing thereby providing an enclosed bus-duct which may be easily installed in manufacturing plants and other locations requiring a power-distribution system.

Since numerous changes may be made in the above-described construction and different embodiments of the invention may be made without departing from the spirit and scope thereof, it is intended that all matter contained in the foregoing description or shown in the accompanying drawings shall be interpreted as illustrative and not in a limiting sense.

I claim as my invention:

1. A multi-phase bus structure comprising, a pair of right angle bars and a flat bar disposed in a T formation, insulating means disposed between said bars, a curved yoke surrounding the bars, insulating blocks disposed between the bars and the yoke, said blocks having curved outer surfaces engaging substantially the entire inner surface of the curved yoke, the radius of said outer surface of one of said blocks being different from the others, and means for drawing the yoke together to compress the blocks against the bars.

2. A multi-phase bus structure comprising, a pair of right angle bars and a flat bar disposed in a T formation, insulating means disposed between said bars, a curved yoke surrounding the bars, insulating blocks disposed between the bars and the yoke, said blocks having curved outer surfaces engaging substantially the entire inner surface of the curved yoke, the radius of said outer surface of one of said blocks being different from the others, and means for resiliently drawing the yoke together to compress the blocks against the bars.

3. A multi-phase bus structure comprising, a pair of right angle bars and a flat bar disposed in a T formation, insulating means disposed between said bars, a curved yoke having a semi-circular section and a segmental section surrounding the bars, said segmental section having a greater radius than the semi-circular section, insulating blocks disposed between the bars and the yoke, and means on said yoke for retaining said blocks in position without attaching the blocks to the yoke.

4. A multi-phase bus structure comprising, a pair of right angle bars and a flat bar disposed in a T formation, insulating means disposed be-

75

tween said bars, a curved yoke having a semi-circular section and a segmental section surrounding the bars, said segmental section having a greater radius than the semi-circular section, and insulating blocks disposed between the bars and the yoke, said blocks having curved outer surfaces engaging substantially the entire inner surface of the curved yoke, the radius of said outer surface of one of said blocks being different from the others.

5. A multi-phase bus structure comprising, a pair of right angle bars and a flat bar disposed in a T formation, insulating means disposed between said bars, a sectional curved yoke surrounding the bars, insulating blocks disposed between the bars and the yoke, said blocks having curved outer surfaces engaging substantially the entire inner surface of the curved yoke, the radius of said outer surface of one of said blocks being different from the others, means for drawing the sections of the yoke together to compress the blocks against the bars, a rectangular housing enclosing the bars, and means on the sides

of the housing cooperating with said drawing means to support the yoke in the housing.
